UNITED STATES PATENT OFFICE

GRANVILLE A. HUMASON, OF HOUSTON, TEXAS

PUMPING APPARATUS

Application filed July 25, 1932. Serial No. 624,425.

My invention relates to pumping equipment for raising liquid from deep wells.

My invention has for its object the provision of an apparatus whereby the oil may be lifted to the surface with a minimum of expense. It includes the provision with or without a pump rod of pneumatically operated means for aerating and raising the column of liquid from the well.

10 I contemplate the provision of an apparatus which may be operated by the pressure of fluid alone and in which, when desired, the pump rod may be entirely dispensed with.

I have as a further object to provide an 15 apparatus which may be easily installed and which will operate for long periods without material wear.

The invention resides particularly in the construction of the parts making up my 20 equipment, a detailed description of which will later be given.

Referring to the drawings herewith, Fig. 1 is a side view partly in elevation and partly in central vertical section of the upper end 25 of my pumping equipment.

Fig. 2 is a similar view through the well casing showing the lower end of my apparatus.

Fig. 3 is a transverse section on the plane 30 3—3 of Fig. 1.

Fig. 4 is a similar transverse section on the plane 4—4 of Fig. 1.

Fig. 5 is a side view partly in elevation and partly in section of the upper end of a similar 25 equipment in which the plunger is operated through fluid pressure alone; and

Fig. 6 is a similar view of the lower end of the apparatus shown in Fig. 5.

In carrying out my invention I provide the 40 usual well casing 1, to the lower end of which may be connected the strainer 2. At the upper end of the well casing I provide a casing head 3 of special construction to receive my pumping equipment. The lower end of 45 the casing head is provided with an internal shoulder 4, upon which may be seated a packing member comprising a lower ring 5, a hollow expansible packing member 6 connected therewith, and an upper metal ring 7. Said 50 rings 5 and 7 are connected with the cylin-

drical rubber packing member by having the ends of said packing member dovetailed to engage within mating grooves in the two rings. The interior of the packing member is hollow and an opening 8 is provided in one 55 side thereof to allow fluid to pass therefrom to an outlet port 9 in the casing head. A passage 10 is provided through the lower end of the packing member and ring 5 to the chamber within the packing member. A 60 valve 11 normally closes the passage 10 against fluid entering the well, but allows fluid from the well to pass upwardly to the outlet port 9 and tending to expand the 65 packer 6.

Above the packing member and connected therewith is a bushing 12. This bushing comprises a ring having an inner tapered seat 13 therein to receive the tapered lower end 14 of an upper head 15. The bushing 70 12 is connected with the upper ring 7 of the packing member by providing an annular groove 16 in the lower side of the bushing to receive upwardly projecting arms 17 upon the ring 7, said arms engaging within said 75 groove and having an outer flange thereon adapted when rotated to lock with an inwardly extending flange 18 shown in the drawings. The bushing 12 is in turn engaged within the upper end of the casing head in 80 a similar manner. Lateral projections 19 on the bushing engage through openings 20 in an inwardly extending flange 21 upon the casing head. Said projections 19 are adapted when rotated to engage under said flange 21 85 and hold the same against removal.

The upper head 15 has a construction somewhat similar to the casing head. Its tapered lower end fits within the seat 13 in the bushing 12 and may be latched in place by latch 90 members 22 in the bushing engaging within a groove 23 in the lower tapered end of the head. The latch is automatically operated to engage against the tapered end by a spring 24 about the latch, as will be understood from 95 Fig. 1.

The head 15 has a lateral pipe 25 connected therewith and above this pipe is a shoulder 26 to receive a packing member similar in construction to the packing member 6. It has 100

a lower metal ring 27, a hollow rubber packer 28, and an upper ring 29. A lateral opening 30 from the inner chamber 31 in the packing member is normally closed by means of a 5 bull plug 32 in the side of the head.

Above the packing member the head is partially closed by a ring or bushing 33 screwed within the upper end of the head and having an inner tapered seat 34 to receive slips for supporting the pump rod 35 when desired.

The pump rod extends downwardly into the tubing 36, which is suspended from the lower end of the head 15. Said tubing has 15 adjacent the lower end a packer 37, which may be of any ordinary construction, adapted to close the space between the tubing and the casing.

Below the packer the tubing has a nipple 20 38, the lower end of which is closed by the plug 59. The nipple 38 has therein a valve sleeve comprising a sleeve 39, an upper cup 40, and a lower packing ring 41. Said packing ring has its lower side tapered in cross 25 section to fit within a seat 42 at the inner end of a passage 43, through the body of the nipple. Thus the incoming fluid through the ports 43 will raise the valve sleeve 39, but the passage of fluid downwardly through the 30 said ports 43 will be prevented.

Above the packer I provide a plurality of outlet ports 44, which communicate with the space between the tubing and the casing and have a valve member 45, similar to the valve 35 39, which slides upon the outer surface of the tubing and seats at 46 within openings from the tubing. Thus, raising of this valve will allow the outlet of fluid from the interior, but it will drop to prevent the passage of 40 fluid from the casing to the interior of the tubing.

Spaced upwardly above the valve 45 is a similar valve 47, tending to control the outlet ports 48 from the tubing in the same manner 45 as in the case of the outlets 44.

At the lower end of the sucker rod is a plunger which includes an inner body 49 having upper and lower cups 50 and 51, respectively. These cups are presented in opposite 50 directions and are held in place spaced apart by a spacing sleeve 52. It will be seen that this plunger is in effect a solid plunger although an interior cavity 53 is provided for purposes of lightness and buoyancy.

55 In the operation of this pump it will be assembled as shown in the drawings. The packing member 6 for the tubing will be placed in position with the bushing 12 thereon and the tubing will then be inserted downwardly therethrough with the head 15 at the upper end of said tubing latched within the upper end of the bushing 12. The pump rod will be packed around by the packer 28 in the head and the ring 33 will be screwed in 60 place to receive the supporting slips. The

plunger will be reciprocated through the pump rod 35 in the usual manner. To assist the operation of the plunger air or other fluid will be pumped into the casing through the pipe 25 and will circulate downwardly 70 against the upper side of the plunger. On the downward stroke the plunger will force the liquid drawn into the tubing below the said plunger outwardly through the ports 48 and 46 to the interior of the casing. 75

As the plunger passes the outlet ports 38 an escape will be allowed for the air or other fluid above the plunger so as not to interfere with the return upward stroke of the plunger. On the upward stroke of the plunger the valve 45 will seat and liquid will be drawn 80 into the tubing through the ports 43, filling the tubing below the plunger. As the plunger passes the ports 48 they will also be closed, preventing the entrance of fluid from outside 85 the tubing to the interior thereof. On the downward stroke the operation will be repeated.

It is to be noted that the working stroke 90 of the plunger, which is a downward stroke, will be assisted by the air pumped in above the plunger. This air under pressure will escape through the ports 48 to assist in lifting the column of liquid being raised by the pump and will materially lessen the work of 95 pumping. Any sand or foreign material entering the tubing through the ports 43 will drop out of the liquid into the closed lower end 39 of the tubing, where it will in no way interfere with the operation of the device. 100

The plunger is a particularly cheap and economical construction and will operate for long periods of time. This will result largely from the fact that the fluid pressure above and below the plunger are nearly equalized, that is, the air or gas pressure above the 105 plunger on the downward stroke is very nearly equal to the pressure below the plunger, tending to force the liquid upwardly past the packing members. There will for this reason be only a small tendency for liquid and sand 110 to pass the plunger, and wear on the plunger and barrel will be greatly decreased and the life of the apparatus will be greatly prolonged. Not only will the air pressure above the plunger assist in the operation of the plunger, and also assist in preventing leakage of fluid past the plunger, but will aerate and lift the liquid through which it passes 115 when it is released from the tubing.

The air escaping in this manner will pass off with the liquid through the passages 10 and the outlet port 9 and will by its pressure within the packing members 6 tend to maintain a seal about the tubing within the casing head. A similar effect is obtained about the pump rod through the pressure of the gaseous fluid within the chamber 21 of the upper 120 packer 28.

In my second embodiment disclosed in Figs. 5 and 6 the structures are similar. However, I do not use the packer at the upper end of the tubing head 15, but close the said head by means of a bushing 33' within which is screwed a plug 54. I do away entirely with the sucker rod and at the upper end 55 of the plunger I screw a post 56 having a head 57 thereon to be engaged by a fishing tool, by means of which the plunger may be withdrawn when desired.

In the operation of this device the plunger will be forced on its downward stroke entirely through the pressure of fluid forced into the upper end of the tubing. The plunger will be moved downwardly to discharge the liquid from the tubing through the valve control ports, as previously described. When the plunger has past the openings 48 the pressure fluid accumulated above the plunger will escape to the outside, relieving the pressure above the plunger and allowing the liquid at the lower end of the well to rise upwardly in the tubing, moving the plunger upwardly above the incoming liquid.

This plunger is also hollow and will be easily floated upwardly by the liquid when the pressure of fluid has exhausted. After the plunger has moved to the upper end of its stroke by the liquid in the well, tending to rise to its ordinary level in the tubing, the pressure fluid will again accumulate above the plunger and will soon move it again on its downward stroke, repeating the operation previously described.

In this device I am enabled to do away with the necessity of a pump rod extending to the surface, the pump is operated entirely through fluid pressure and the life of the equipment will be extended through the fact that no excessive wear takes place in the operation of the device. The advantages of this will be obvious to those skilled in the art.

What I claim as new is:

1. A pump of the character described including a well casing, a casing head thereon, a tubing in said casing, means to support said tubing in said casing head, a packing about said tubing adjacent its upper end, a liquid inlet adjacent its lower end, an outlet from said casing, said packing being expanded by fluid flowing to said outlet, a plunger in said tubing closing the passage upwardly therethrough, and means whereby said plunger may be moved downwardly to force liquid from said tubing above its lower end and upwardly about said tubing to said outlet.

2. A pump of the character described including a well casing, a casing head thereon, a tubing in said casing, means to support said tubing in said casing head, a packing about said tubing adjacent its upper end, an outlet from said casing, said packing being expanded by fluid flowing to said outlet, a plunger in said tubing closing the passage

upwardly therethrough, a liquid inlet adjacent the lower end of said tubing, an outlet above said inlet, and means whereby said plunger may be moved downwardly to force liquid from the outlet in said tubing to said casing outlet, said means including an inlet pipe for fluid under pressure.

3. A pump including a well casing, a fluid outlet therein, a tubing supported therein, a packer on said tubing adjacent its lower end, an inlet to said tubing below said packer, a packing member acting to seal off the tubing within the upper end of said casing, a plunger closing the passage in said tubing, means to conduct pressure fluid into the upper end of said tubing, valve controlled ports in said tubing above said packer to furnish an outlet to said casing for liquid being pumped, said liquid also acting to seal said packing member.

4. A pump including a well casing, a fluid outlet at its upper end, a tubing supported therein, a packer on said tubing adjacent its lower end, an inlet to said tubing below said packing, a packing member acting to seal off the tubing within the upper end of said casing, a plunger closing the passage in said tubing, means to conduct pressure fluid into the upper end of said tubing, valve controlled ports in said tubing above said packer to furnish an outlet to said casing for liquid being pumped, said liquid also acting to seal said packing member, said pressure fluid also being adapted to escape through said ports when said plunger has passed the same and assist in raising said liquid.

5. In a pump, a well casing, a casing head, a hollow packing member in said head, a bushing thereon, a tubing supported on said bushing, a fluid inlet at its lower end, means to conduct gaseous fluid into the upper end of said tubing, outlet ports near the lower end of said tubing, a plunger in said tubing to force liquid in said tubing through said ports to the interior of the casing, a packer below said outlet ports, and an outlet from the casing for said liquid through said hollow packing member.

6. In a pump, a well casing, a casing head, a hollow packing member in said head, a bushing thereon, a tubing head fitting within said bushing, a tubing secured to said head and having an inlet adjacent its lower end, means to automatically lock said head in said bushing, means to conduct gaseous fluid into the upper end of said tubing, outlet ports near the lower end of said tubing, said pressure fluid acting to depress the liquid in said tubing to force said liquid in said tubing through said ports to the interior of the casing, and an outlet from the casing for said liquid through said hollow packing member.

7. In a pump, a well casing, a casing head thereon, a tubing supported in said casing head, a fluid inlet at the lower end thereof,

means to seal about said tubing in said casing head, means to seal about said tubing adjacent the lower end thereof, a slidable plunger closing the passage through said tubing, a plurality of valves opening outwardly from said tubing between said sealing means, and means including a line to conduct pressure fluid into the upper end of said tubing above said plunger to force said plunger downwardly in said tubing to discharge liquid upwardly in said casing, there being an outlet for said liquid at the upper end of said casing.

8. In a pump, a well casing, a casing head thereon, a tubing supported in said casing head, a fluid inlet at the lower end thereof, means to seal about said tubing in said casing head, means to seal about said tubing adjacent the lower end thereof, a slidable plunger closing the passage through said tubing, a plurality of valves opening outwardly from said tubing between said sealing means, and means including a line to conduct pressure fluid into the upper end of said tubing above said plunger to force said plunger downwardly in said tubing to discharge liquid upwardly in said casing, there being an outlet for said liquid at the upper end of said casing, said valves being arranged on said tubing to allow an outlet for said pressure fluid to the casing when said plunger has made its downward stroke.

9. In a pump including a tubing and a plunger free to move therein the entire length of said tubing, the improvement comprising sealing the space around the lower end of said tubing, moving said plunger downwardly by gaseous fluid pressure above the same and thereby forcing the liquid being pumped through outlets in said tubing into said well above said sealing means, exhausting the fluid pressure above said plunger through said outlets into said liquid and raising said plunger on its upward stroke by the liquid in the well.

10. In a pump including a well tubing, the method of lifting liquid in said well, comprising introducing a barrier into said tubing to the liquid level therein, sealing the space around the lower end of said tubing and the wall of the well, moving said barrier downwardly by gaseous fluid pressure to discharge liquid from said tubing to the well above said sealing means, exhausting said gaseous fluid with said liquid from the tubing at the end of the downward stroke of said barrier to aerate said liquid, and then raising said barrier by the pressure of liquid in the well.

11. In a pump including a well tubing, a method of lifting liquid in said well, comprising sealing the space around the lower end of said tubing and the wall of the well, moving said liquid downwardly by gaseous fluid pressure in said tubing to discharge liq-

uid from said tubing to the well above said sealing means, discharging said gaseous fluid from said tubing at a predetermined level into said liquid to aerate the same, and thus relieving the fluid pressure in said tube to permit the liquid to again rise in said tubing.

In testimony whereof I hereunto affix my signature this 20th day of July, A. D. 1932.
